TREAD ASSEMBLY

James A. Wahlfeld, 216 W. Stratford Drive, Peoria, Ill.
Filed Jan. 11, 1960, Ser. No. 1,500
5 Claims. (Cl. 20—64)

The present invention relates to a tread assembly for use in connection with doorways. More particularly, it has to do with a treadway platform especially suited for use with outer doors of a kind providing a weather barrier at the sill. The present application is a continuation-in-part of my co-pending application, Ser. No. 801,102, filed March 23, 1959.

It is well known that air leakage and consequent heat loss are particularly troublesome in the case of doors at the entrance between the exterior and interior of a house or other enclosure. The lack of an effective seal between the door and underlying floor not only permits the escape of warm air to the outside and, conversely, the entrance of cold exterior air but the metal thresholds often used at the present also serve to conduct heat past the door resulting in heat loss and interior frosting of the threshold.

The aforementioned co-pending application discloses a threshold assembly having most effective sealing capabilities. Described and claimed in that application are several embodiments all of which feature a flexible sealing element forming the actual threshold against which the bottom of the door is engaged when closed. One feature of the assemblies disclosed in the aforesaid co-pending application is the wide flexibility of their adaption to many different door sill contours, and variation of interior floor levels. However, certain advantages of that application have been supplemented and further advantages attained with the present invention for certain installations and improved modes of attachment as where stone, or different pitches or levels, or an unfinished threshold might be present.

It is accordingly a general object of the present invention to provide a combination door frame, door sill or threshold assembly which is simple and readily installed and eliminates the special preparations required to install other door sills.

Another object of the present invention is to provide a tread assembly which may be affixed in place with a minimum of securing means such as wood screws.

A further object of the present invention is to provide a sill and threshold assembly which is capable of accommodating various floor constructions and various interior finished floors.

A door sill and threshold assembly constructed in accordance with the present invention includes a treadway defining a platform mountable to project away from the sealer which engages the door in its closed position. The platform projects beyond the floor construction, whether wood or concrete, and is turned downwardly to form a front edge plate. A joint member is presented inwardly from the front edge plate to face the edge of the floor construction. On the under side of the platform is a coupling member facing downwardly. Cooperating with the platform is an anchor affixable over the front edge of the floor construction and having a joint element projecting outwardly and lockingly engageable with the joint member together with a coupling element projecting upwardly and engageable with the coupling member.

The features of the invention which are believed to be novel are set forth with particularity in the appended claims. The invention, together with further objects and advantages thereof, may best be understood by reference to the following description taken in conjunction with the accompanying drawings, in which:

FIG. 1 is a fragmentary perspective view of a doorway

2

frame having a door sill and threshold assembly of the present invention installed thereon;

FIG. 2 is a cross-sectional view taken along the line 2—2 in FIG. 1;

FIG. 3 is a cross-sectional view showing installation of what is commonly called slab construction; and

FIGS. 4a, 4b and 4c show adaptability to various interior finish floor coverings.

As shown in FIGS. 1 and 2, 3 and 4 for purposes of illustrating the present invention, a conventionally formed doorway includes a floor construction 10 composed of sub-floor or sub-sill 11 and a box framing member 12 or of a concrete slab 11' (FIG. 3). At one side of the doorway is the usual upright jamb 13, the front edge of which is partially covered by trim 14. A recess 15 is cutout in jamb 13 in the usual manner to accommodate a door (not shown) suitably hinged to the door frame and closable against jamb 13. For weather protection along the vertical margins of the door, weather stripping 16 runs vertically along the surface of recess 15 facing the door edge.

The entire sill and threshold assembly 20 includes a pair of channel sections 21 and 22, preferably of extruded aluminum, and a sealing strip or sealer 23 interlockingly secured between channel sections 21 and 22. The inward terminus of channel section 21 includes a downwardly projecting leg 24 having its lower end turned outwardly to define a footing restable upon sub-floor 11. Leg 24 and the inward edge of channel section 21 define a recess 26 running horizontally along the length of channel section 21. In addition, an upturned lip projecting inwardly from leg 24 is formed into an arcuate shoulder 27, the latter also running horizontally the width of the doorway. Shoulder 27 together with leg 24 defines an arcuate hinge seat 28 also running horizontally the width of the assembly. The upper surface of channel section 21 defines a platform projecting slightly downwardly and outwardly away from sealer 23. The upper surface of the platform is formed to define a plurality of ribs which afford a roughened non-skid surface as well as contributing to added rigidity. In addition, a suitable plastic embedded with minute cinder particles or the like is preferably secured in strips longitudinally in the recesses between the ribs to even further contribute to safe traction on the platform surface.

Channel section 22 has an inwardly and downwardly depending leg 30. Leg 30 is preferably tapered downwardly to define a knife edge embeddable in the top surface of the interior floor covering 31. Adjacent sealer 23, member 22 terminates with a shape defining recess 33 running across the width of the doorway. The lower wall 34 of recess 33 has a downwardly recessed intermediate section 35 and projects away from leg 30 with its free end shaped to define an arcuate hinge 36 receivable over shoulder 27 and into the hinge seat. In order to provide a heat barrier between treadway section 21 and interior section 22, a semi-cylindrical joint element 38 is disposed over shoulder 27 between the latter and hinge 36. Joint element 38 may consist of a plurality of short sections for easier installation and is of a heat insulative material.

Channel sections 21 and 22 are held rigidly in position on sub-floor 11 by a plurality of wood screws 40 which project through recessed portion 35 of member 22. In the case of slab 11', screws 40 are secured with conventional masonry anchors 40' (FIG. 3). It will be noted that hinge seat 28 and hinge 36 have sufficient play to permit section 22 to articulate appreciably with respect to section 21. Consequently, differences in height between floor surface 31 and sub-floor 11 are easily accommodated. When screws 40 are tightened, interior channel section 22 is drawn toward floor surface 31, bringing leg 30 into sealingly tight frictional engage-

ment therewith. Similarly, leg 24 is also pulled tightly against sub-floor 11.

Sealer 23 preferably is formed of a material such as extruded grey vinyl; it has the characteristics of being both resilient and compressible as the result of which its convex top wall 42 is compressible downwardly upon closure of a door thereagainst, while at the same time it engages the bottom surface of the door to provide a weather-tight barrier. Suitable materials include natural or synthetic rubber, as well as various plastics. Sealer 23 includes oppositely projecting flanges 43 and 44 respectively engageable in recesses 33 and 26. For added strength and durability, flanges 43 and 44 are interconnected by a web 45.

It will be observed that treadway platform 21 serves to replace the wooden sill heretofore normally furnished with door frames. The platform projects beyond sub-floor 11 and is then turned downwardly to define a front edge plate 47. In accordance with the present invention, the facility and varied adaptability of mounting the tread assembly is enhanced by a unique intercorrelation of the elements. To this end, a joint member 48 projects inwardly from the lower marginal edge of plate 47. In this specific embodiment it preferably is formed to define an elongated socket running along the length of plate 47. Also included are a pair of rails projecting downwardly from platform 21 to define a recess 49 extending the length of the platform underside and forming a coupling member.

Cooperating with the treadway assembly is anchor strip 50. Strip 50 is generally L-shaped, having a shorter leg or lip 51 projecting over the front edge of sub-floor 11 and a longer leg 52 disposed along the front edge surface of sub-floor 11 and down over box 12. Anchor 50 is secured to floor construction 10 by wood screws 53 sunk into box 12 or concrete nails 53' driven into slab 11'. Projecting outwardly from leg 52 is a strut 54 terminating in a joint element lockingly engageable with joint member 48; accordingly, the free end of strut 54 forms an elongated ball joint receivable in the socket defined by joint member 48. Projecting upwardly from anchor 50 is a stud 55 the free end of which defines a coupling element receivable in recess 49.

Mounting of the entire assembly is simple and easy. First, treadway section 21 is trimmed to fit snugly within the width of a doorway in abutting relationship with the jamb and trim elements. Similarly, interior section 22 is cut to fit within the door frame. Anchor 50, cut to proper length is coupled to platform section 21 merely by inserting the elongated ball joint end of strut 54 within the socket of joint member 48. As the two pieces slide into matching position, the free end of stud 55 is inserted between the rails of coupling recess 49. Upon placing platform section 21, anchor 50 comes into position over the upper corner of floor construction.

The two principal sections 21 and 22 are then tightened into position by screws 40 after which sealer 23 is slipped into recesses 43 and 44, having first been trimmed to proper length. With sealer 23 in place, its arcuate top wall 42 may be pinched and a slight downward force applied; this has the effect of deforming web 45 to insure that it nests properly within recess 35. Thereupon the web is momentarily pressed downwardly from the top to force the lower wall into a downwardly arched configuration if desired and then released to permit the upper wall to resume its upwardly arched position. Thereafter, web 45 tends to maintain an arched configuration under a stress which acts to resist inadvertent displacement of the sealing strip from its interlock with the two rigid sections. Finally, screw 53 is sunk and tightened down.

FIGS. 2, 3, 4a, 4b and 4c serve to exemplify the wide versatility of adaptation to various flooring arrangements. FIG. 2 depicts the combination of sub-floor, carpeting and underlays. As indicated previously, FIG. 3

pertains to concrete slab construction with the interior covered with tile or the like; in this instance, leg 38' may be formed slightly different than as shown in FIG. 2 in order to accommodate the difference in interior surface height. FIGS. 4a and 4b illustrate the flexibility as between partial and full thickness flooring 31a and 31b respectively, utilizing a spacer 60 on top of sub-floor 11 when accommodating the full thickness. FIG. 4c illustrates use of the apparatus in connection with the combination of tile or the like and an underlayment as indicated at 31c. As shown in FIGS. 3 and 4, nails 61 may be driven upwardly through the end margins of platform 21 and into the lower end portion of jamb 13 for added rigidity.

It will be observed that all rigid portions are easily manufactured with conventional techniques. Moreover, they are shaped to permit ready packaging for shipment. Yet they assemble interlocking to form an extremely rigid treadway assembly which may be quickly assembled and affixed into place. The inventive assembly completely eliminates any necessity for cutting away the sub-floor, cutting down the box member, chamfering the joist or crippling the sub-floor. All of such operations are required in the installation of the ordinary door frame having a wooden sill.

While a particular embodiment of the present invention has been shown and described, it will be obvious to those skilled in the art that changes and modifications may be made without departing from the invention in its broader aspects. Accordingly, the aim in the appended claims is to cover all such changes and modifications as follow in the true spirit and scope of the invention.

What is claimed is:

1. A tread assembly secured over a door sill in locking engagement with a threshold sealer to provide a weather barrier with a door comprising a treadway, a sealer secured in the treadway, said treadway extending outwardly from the sealer beyond the door sill, a front edge plate integrally formed with and extending downwardly from the treadway beyond said sill, a joint member facing inwardly from and running the width of the front edge plate, said joint member integrally formed on the lower edge of the front edge and an anchoring strip secured on the front edge surface of the sill having an outwardly extending strut interlocking with said joint member to retain said treadway to said sill whereby the sealer is in alignment with the door to effect a weathertight barrier when the door is in closed position.

2. A tread assembly secured over a door sill in locking engagement with a threshold sealer to provide a weather barrier with a door comprising a treadway, a sealer secured in the treadway, said treadway extending outwardly from the sealer beyond the door sill, a front edge plate integrally formed with and extending downwardly from the treadway beyond said sill, a first joint member integrally formed with and running the width along the under side of said treadway, a second joint member integrally formed on the inner surface of the front edge plate and running the width thereof, and an anchoring strip secured on the front edge of the sill having an upwardly extending stub received in said first joint member and an outwardly extending strut interlocking with said second joint member to retain the tread assembly to the sill whereby the sealer is retained in alignment with the door to effect a weathertight barrier when the door is in the closed position.

3. A tread assembly secured over a door sill in locking engagement with a threshold sealer to provide a weather barrier with a door comprising an outer treadway section, a sealer having one edge secured in the outer treadway section, said outer treadway section extending outwardly from the sealer beyond the door sill, a front edge plate integrally formed with the outwardly extending edge of said outer section and extending downwardly therefrom, a hinge member formed on the inner edge of said outer treadway section extending the width thereof,

a joint member facing inwardly from and running the width of the front edge plate, said joint member integrally formed on the lower edge of the front edge plate, an inner treadway section, said inner treadway section interlocking with said hinge member and securing the other edge of said sealer and an anchoring strip secured on the front edge of the sill having an outwardly extending strut interlocking with said joint member to retain said inner and outer treadway to said sill whereby the sealer is retained in alignment with the door to effect a weathertight barrier when the door is in the closed position.

4. A treadway assembly secured over a door sill in locking engagement with a threshold sealer to provide a weather barrier with a door comprising an outer treadway section, a sealer having one edge secured in the outer treadway section, said outer treadway section extending outwardly from the sealer beyond the door sill, a front edge plate integral with the outwardly extending edge of said outer section and extending downwardly therefrom, a hinge member formed on the inner edge of said outer treadway section extending the width thereof, a first joint member integrally formed with and running the width along the underside of said outer treadway section, a second joint member integrally formed on the inner surface of the front edge plate and running the width thereof, an inner treadway section, said inner treadway section interlocking with said hinge member and securing the other edge of said sealer and an anchoring strip secured on the front edge of the sill having an upwardly extending stub 30 received in said first joint member and an outwardly ex-

tending strut interlocking with said second joint member to secure the tread assembly to the sill whereby the sealer is retained in alignment with the door to effect a weathertight barrier when the door is in the closed position.

5. A tread assembly secured over a door sill in locking engagement with a threshold sealer to provide a weather barrier with a door comprising an outer treadway section, an inner treadway section, a hinge member on said outer treadway section interlocking said outer treadway section with said inner treadway section, a sealer releasably retained between and by said outer and inner treadway sections, said outer treadway section extending outwardly from the sealer, a front edge plate extending downwardly from the treadway beyond said sill, and an anchoring strip secured on the front edge of the sill interlocking with said treadway and said front edge plate to retain said inner and outer treadway sections to said sill, positioning said sealer in alignment with a door to effect a weather barrier when the door is in the closed position.
